US00D892825S

(12) **United States Design Patent** (10) Patent No.: **US D892,825 S**
(45) Date of Patent: **** Aug. 11, 2020**

(54) **DISPLAY SCREEN OR PORTION THEREOF WITH GRAPHICAL USER INTERFACE**

(71) Applicant: **BostonGene Corporation**, Lincoln, MA (US)

(72) Inventor: **Alexander Bagaev**, Moscow (RU)

(73) Assignee: **BostonGene Corporation**, Waltham, MA (US)

(**) Term: **15 Years**

(21) Appl. No.: **29/694,305**

(22) Filed: **Jun. 10, 2019**

(51) LOC (12) Cl. **14-04**

(52) U.S. Cl.

USPC **D14/485**

(58) **Field of Classification Search**

USPC D14/485-495

CPC G06F 17/211; G06F 17/212; G06F 3/1251; G06F 3/0481; G06F 2203/04807

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines showing the display screen or portion thereof and graphical elements within the display screen form no part of the claimed design.
